DESIGN FOR AN ALPHABET FOR FORMING MONOGRAMS OR THE LIKE

Michael Chernow, Brooklyn, N. Y.

Application November 17, 1934, Serial No. 54,061

Term of patent 7 years

To all whom it may concern:

Be it known that I, Michael Chernow, a citizen of the United States and residing at Brooklyn, in the county of Kings and State of New York, have invented a new, original, and ornamental Design for an Alphabet for Forming Monograms or the like, of which the following is a specification, reference being had to the accompanying drawing, forming part thereof, and in which

Fig. 1 is a face view of the alphabet showing my new design.

Fig. 2 is a perspective view showing one of the letters of the alphabet.

The characteristic feature of the design is the slender curved conformation in which each letter other than the V and W is wider at the base than at the top, affording the suggestion of slenderness combined with stability.

I claim:

The ornamental design for an alphabet for forming monograms or the like, substantially as shown and described.

MICHAEL CHERNOW.
